UNITED STATES PATENT OFFICE.

CHARLES F. TAYLOR, OF HARTFORD, CONNECTICUT.

MACHINE FOR BINDING PADS OR TABLETS.

SPECIFICATION forming part of Letters Patent No. 793,108, dated June 27, 1905.

Application filed August 17, 1904. Serial No. 221,086.

To all whom it may concern:

Be it known that I, CHARLES F. TAYLOR, a citizen of the United States, residing at Hartford, in the county of Hartford and State of Connecticut, have invented a new and useful 5 Machine for Binding Pads or Tablets, of which the following is a specification.

This invention relates to a machine which is designed to apply a strip of flexible material coated on one side with adhesive compound to the edges of packets or bunches of sheets of paper that are fed along the machine for the purpose of binding the sheets which are afterward trimmed or cut into 15 pads, tablets, or composition-books of the desired size for memorandum, writing, and drawing purposes.

The object of the invention is to produce a machine which will feed the packets of paper, 20 render a binding-strip adhesive, apply the adhesive strip to the edges of the packets, cut the strip behind each bound packet, and deliver the bound packets to a drier.

In the machine which is illustrated as embodying this invention packets or bunches 25 containing the required number of sheets of plain or ruled paper of the desired size are pushed along a table to jaws which grasp the packets from above and below and carry 30 them suitably spaced past a strip of cloth which is drawn from a reel and coated with glue on one side and is folded by rolls and a brush about the edges of the packets as they are carried along. The strip of cloth is cut 35 off behind each bound packet by a pair of shears, and a pair of rolls deliver the bound packets after the strip is cut onto the vertically-movable arms of a drier, which retain 40 the packets until they are removed by an attendant.

Figure 1 of the views shows a rear elevation of the machine. Fig. 2 shows an enlarged elevation of the holder for the rolls 45 that are used to press the glued strip of cloth to the top and bottom faces along the edges of the packets. Fig. 3 shows a plan of these rolls and the holder. Fig. 4 shows an elevation of the drier end of the machine. Fig. 5 shows a part of the drier-feed mechanism. Fig. 6 shows a detail of the drier and its

guide. Fig. 7 shows parts of several of the drier-slats and the connecting-chain. Fig. 8 shows in plan, on larger scale, the rolls, brush, and finger which press the glued strip to the edges of the packets and the shears which 55 cut the strip. Fig. 9 shows in perspective the table with the front guides and the packet feeding mechanism. Fig. 10 shows a vertical section of the frame on the plane indicated by the line 10 10 of Fig. 1. Fig. 11 shows a 60 front elevation of a portion of the machine. Fig. 12 shows a rear elevation of a portion of the machine. Fig. 13 shows a section, on larger scale, of the packet-grasping mechanism on the plane indicated by the line 13 13 65 on Fig. 12. Fig. 14 shows an elevation of the same with parts broken away to show the construction. Fig. 15 shows a plan of the packet carrying and guiding parts and the strip applying and pressing mechanisms. 70

Packets or bunches P, containing the required number of plain or ruled sheets of paper of the desired size, are placed on the top of the table 1 and are pushed forwardly by a head 2, that is fastened to a rod 3, 75 Figs. 1, 9, 11. The rod 3 is adjustably connected with an arm 4, that is free to slide on a bar 5, which is attached to the end of the frame 6. A link 7 connects the arm with the upper end of a lever 8, which is pivoted to a 80 bracket 9, that is attached to a frame 10, fastened to the legs 11. This lever carries a roll 12, which engages a cam-groove 13 in the face of the cam-pulley 14, that is mounted on the cam-shaft 15, which has a gear 16 in 85 mesh with a pinion 17 on a shaft 18, bearing a driving-pulley 19, Figs. 1-11. The rotation of the pulley through the pinion and gear causes the cam-groove to oscillate the lever, and this reciprocates the arm and rod with 90 the pusher-head at the proper time for feeding forwardly the packets which are placed upon the table.

The pusher-head advances the packets between a pair of gripping-jaws, which after 95 being closed together carry the packets forwardly still farther. The upper gripping-jaw 20 is adjustably connected with a horizontal plate 21, that is attached to a vertical slide 22. This slide is movable up and down 100

in a carriage 23, that is movable along the inside of the front of the frame, Figs. 9, 10, 12, 13. The lower gripping-jaw 24 is attached to a horizontal bar 25, that is connected with a 5 vertical slide 26, which is movable up and down in the carriage 23, Figs. 9, 10, 12, 13.

The vertical slides, which carry the gripping-jaws, are reciprocated oppositely, so as to cause the jaws to move toward and from 10 each other by the horizontal movement of the slide 27, which has inclined slots 28, into which pins project from the slides, Figs. 12, 13, 14. When the horizontal slide is pushed forwardly, the slots and pins cause 15 the vertical slides to close the jaws together and grip two packets between them. When the horizontal slide is drawn backwardly, the slots and pins cause the vertical slides to open the jaws from each other, Figs. 12, 13, 14.

20 The slotted slide is provided with a hook 29, that is adapted to be engaged by a hook 30 on an arm 31, that is pivoted to a horizontal slide 32. This latter slide is movable along the inside of the front of the frame and 25 is connected by a link 33 with a bar 34, that is fastened to a block 35, which is movable longitudinally of the machine in a way 36, held above the cam-cylinder 37. This block is moved back and forth by the engagement 30 of the ribs on the cam-cylinder with a roll attached to the under side of the block, Figs. 10, 12. The cam-cylinder by means of the cam-ribs drives the block forwardly and backwardly and causes the slide with the 35 hinged finger to travel forwardly and backwardly. The forward movement of the cam-slide 32 causes the hooked arm 31 to engage the slotted slide 27 and first drive the slotted slide forwardly, so that the slots will close the 40 jaws, and then after the jaws have been closed the continued forward movement of the slide pushes the carriage, with the jaws holding the packets, forwardly past the devices which apply the glued strip along the 45 edge. The return movement of the slide 32 first draws the slotted slide backwardly and opens the jaws from the packets, and then after the jaws are open the carriage is drawn backwardly until the bail 38, that is attached 50 to the hooked arm, encounters a wedge 39 on the top of the frame, Fig. 12, and raises the arm and disengages the hooks. The carriage then stops, with the jaws open, while the cam-slide, with the hooked arm, is drawn backwardly the full throw of the cam.

The backward movement of the jaw-carriage is limited by the position of the wedge 39 on the edge of the frame, the wedge being 55 adjusted according to the length of the packets 60 which are to be carried forward by the jaws. The cam-cylinder and cam-ribs are long enough to reciprocate the hooked arm and jaw-carriage the full distance of the longest packets that will ever need to be fed, and 65 the wedge is adjustable in order that the

hooked arm may be disengaged from the slotted slide and leave the jaw-carriage in such a position that the forward movement of the jaws will be equal to the length of the packets which they are at the moment to 70 carry past the strip-applying devices.

To relieve the shock incident to the forward and backward movements of the jaw-carriage, a block 40 is attached to the carriage in position to engage with a lever 41 at 75 one end and a lever 42 at the other end of the limit of travel of the carriage. These levers are connected with pistons in dash-pots 43, adjustably secured to the front of the frame, Fig. 11.

The upper jaw is moved for varying the space between the jaws by means of an adjustable wedge 44 between the inclined block 45, fastened to the top of the upper jaw, and the horizontal plate which supports 85 the upper jaw, Fig. 9.

To procure such an accurate spacing and travel of the packets as will insure the cutting of the strip between two packets, a block 46 is thrust between the two packets 90 before the jaws are closed. This block is removed before the jaws are opened. The block is mounted on the end of a lever 47, which is pivoted on the upper-jaw carrier, and that extends across the machine and is 95 connected by a link 48 with angle-lever 49. The engagement of the angle-lever with a set-screw 50, arranged on a fixed part, as the jaws reach the forward limit of movement causes the cross-lever to lift the block away 100 from the lower jaw and from between the packets before any backward movement of the jaws takes place. The engagement of the angle-lever with the arm 51, adjustably attached to the frame, as the jaws reach the 105 backward limit of movement causes the cross-lever to drop the block toward the lower jaw and between two packets. The forward movement of the jaws and block occurs before the jaws are closed, so that the 110 packet in advance is pushed forwardly by the block an exact distance. The jaws only hold the advance packet flat. The block keeps the packets separated the required distance and pushes the front one forward properly, 115 Figs. 9, 10, 11.

When the packets are advanced by the pusher-head, they are directed by a guide 52, which is pressed backwardly by springs 53 against rolls 54, loosely mounted on vertical 120 arbors located along the back of the frame, and when the jaws carry the bunches of paper forwardly a guide 55 presses them rearwardly toward the devices which apply the 125 glued strip, which is drawn along by the packets as they are fed by reason of the adhesion of the adhesive compound to the edges of the bunches, Figs. 1, 9.

The strip, which may be cut from any suitable kind of cloth or paper, is wound upon a 130

reel 56, that is supported by a frame 57 back of the machine. The strip in the form of machine shown is carried around rolls 58 to a roll 59, that dips into a glue-vat 60 and applies glue to one side of the strip. The glue is preferably kept hot by a lamp 61, and the surplus quantity is removed from the strip by a scraper 62, Fig. 4. This adhesive of course may be any other suitable compound besides glue, and, if desired, the strip itself may have been previously coated with an adhesive compound, in which case the roll 59 instead of applying the adhesive would simply apply moisture for the purpose of softening the adhesive compound.

After passing the glue-roll the strip turns and runs along rolls 63, loosely mounted on vertical arbors located along the back of the frame. There may be any desired number of rolls on vertical arbors, and the strip of course runs past them with the glued side toward the edge of the packets that are being carried along the top of the table by the jaws and that as they are carried along are pressed toward the rolls by the guide 55. These rolls press the glued strip against the edges of the packets, Figs. 8, 15.

Adjustably attached to the edge of the frame beyond the rolls on vertical arbors is a brush 64, that is arranged so that its bristles will yieldingly press the strip against the edge and on the top and bottom near the edge of the packets as they are carried along, Figs. 8, 15.

Mounted on the edge of the frame beyond the brush is a pair of rolls 65, loosely mounted on vertical arbors, one of which lies below and the other above the edges of the packets. These rolls rub the strip with their flat faces against the upper and lower surfaces of the packets as they are carried along, Fig. 8. Supported beyond the rolls on the vertical arbors are a pair of rolls 66 on horizontal arbors, one of which is arranged to run below and the other above the edges of the packets, so that they will press the strip with their circular faces against the upper and lower surfaces of the packets, Fig. 8. These rolls are loosely held by a frame 67, so that they will press the strip against the surfaces of the packets. The rear faces of these rolls are provided with ratchet-teeth 68, which are engaged by spring-fingers 69, so that the rolls will only turn forwardly, Figs. 2, 3. Mounted in advance of the rolls 66 is an arm 70, which is attached to the frame and that has a bent spring-finger 71, that rubs against the strip and presses it closely to the edges of the packets as they are fed past, Fig. 8.

An upper shear-blade 72, that extends over the path of the strip, is mounted on a vertical slide 73, that is connected by a link 74 with a lever 75. A lower shear-blade 76, that extends below the path of the strip, is mounted on a vertical slide 77, that is con-

nected by a link 78 with the lever 75. The link 74 is connected on one side and the link 78 is connected on the other side of the pivot of the lever 75, Fig. 10. This lever is pulled in one direction by a spring 79 and is swung in the other direction by a cam 80 on the cam-shaft 15, Figs. 1, 8, 10. The rotation of this cam and the oscillation of this lever through the links reciprocates the slides and causes the shear-blades to cut the strip of cloth. The cam is so timed that the shear-blades come together and cut the cloth between the bound packet and the packet following.

When the jaws are opened, the packet in advance is carried forwardly by two pulleys 81 until its front end strikes an adjustable stop 82, which retains it between a pair of drier-arms 83. These pulleys are belted to a shaft 84, which is belted to the cam-shaft, Figs. 1, 4.

The drier in this instance is an elevator. The arms 83 of the drier that is illustrated are fastened to slats 86, that are connected near each end by a chain 87. The chains run around sprocket-wheels 88 on shafts supported at the top and bottom of the drier-frame, Figs. 4, 7. On each end of each slat is a plate 89, that extends between the vertical bars 90, which form part of the drier-frame and which guide the slats as they are carried around by the sprockets and chains, Figs. 4 to 6. On the shaft of the upper sprocket-wheel is a fixed ratchet-wheel 91 and a loose segmental gear 92, on which loose gear is a pawl 93, that is held in engagement with the teeth of the ratchet-wheel by a spring 94. Supported by the head of the drier is a rack 95, that meshes with the segmental gear, Fig. 5. This rack is connected by a rod 96 with a lever 97, that is pivoted to the lower part of the frame, and is oscillated by a cam 98 on the cam-shaft, Figs. 1, 10. The rotation of this cam oscillates the lever and causes the rod at the proper time to reciprocate the rack and oscillate the segmental gear in such manner as to intermittently rotate the upper sprocket wheel. This intermittently feeds the chains and slats with the drier-arms and carries the bound packets up on one side and down on the other side of the drier-frame, Figs. 1, 4. When the bound packets reach the lower portion of the opposite side of the drier from where they entered, they are removed by an attendant.

This machine may be used for applying strips of any suitable fabric cut any desired width and coated with any kind of adhesive to the edges of packets or bunches containing any desired number of sheets of plain or ruled paper of any quality and character which may be cut to the required size for forming pads or tablets or composition-books, but which, as most preferred, are of such length that they are afterward cut up in another

machine into pads, tablets, or books, as the case may be, of the finished size.

The packets are fed into this machine by an attendant, and the machine continues to

5 apply and press down the strip coated with adhesive compound and deliver the bound packets to the drier as long as they are fed and the adhesive strip lasts. This machine is adjustable for various sizes and thicknesses 10 of packets, and by the time the packets reach the lower end of the drier the adhesive is sufficiently hardened to permit the packets to be removed to the trimming or cutting machine or to be stacked away.

15 The invention claimed is—

1. A binding-machine having reciprocating means for intermittently feeding packets of paper, rolls for applying an adhesive strip to the edges, rolls for applying the adhesive 20 strip to the front and back sheets of the packets as they are fed, and means for severing the strip between two packets, substantially as specified.

2. A binding-machine having reciprocating means for intermittently feeding packets 25 of paper, rolls for applying an adhesive strip to the edges, rolls for applying the adhesive strip to the front and back sheets of the packets as they are fed, means for severing the 30 strip between two packets, and means for carrying the bound packets until the adhesive becomes set, substantially as specified.

3. A binding-machine having reciprocating means for intermittently feeding packets 35 of paper, rolls for applying an adhesive strip to the edges, rolls for applying the adhesive strip to the front and back sheets of the packets as they are fed, and means for carrying the bound packets until the adhesive becomes 40 set, substantially as specified.

4. A binding-machine having means for pushing forwardly packets of paper, jaws for grasping and carrying forwardly the packets, means for applying an adhesive strip to the 45 edges and the front and back sheets of the packets as they are carried forwardly, and means for severing the strip between two packets, substantially as specified.

5. A binding-machine having means for pushing forwardly packets of paper, jaws for grasping and carrying forwardly the packets, means for applying an adhesive strip to the edges and the front and back sheets of the packets as they are carried forwardly, means for 50 severing the strip between two packets, and means for carrying the bound packets until the adhesive becomes set, substantially as specified.

6. A binding-machine having a reciprocating pusher for pushing forwardly packets of paper, opening and closing jaws for grasping the packets and carrying them farther forward, means for applying an adhesive strip to the edges of the packets as they are carried forwardly, means for severing the strips 55

between two packets, and means for carrying the bound packets until the adhesive becomes set, substantially as specified.

7. A binding-machine having a reciprocating pusher for pushing forwardly packets of paper, opening and closing jaws for grasping the packets and carrying them farther forwardly, means for applying an adhesive strip to the edges of the packets as they are carried forwardly, means for severing the strip between two packets, vertically - movable arms, means for delivering the packets to the arms, and means for intermittently moving the arms, substantially as specified. 75

8. A binding-machine having opening and closing jaws for grasping and carrying forwardly packets of paper, means for rendering a strip adhesive, rolls for guiding the strip against the edges of the packets as they are carried forwardly, a brush and horizontally-bearing and vertically-bearing rolls for pressing the strip against the edges of the packets, and means for severing the strip between two packets, substantially as specified. 80

9. A binding-machine having reciprocating means for intermittently carrying forwardly packets of paper, means for applying adhesive to a strip of cloth, rolls for pressing the strip against the edges, rolls for pressing the strip against the front and back sheets of the packets as they are carried forwardly, and means for severing the cloth between two packets, substantially as specified. 85

10. A binding-machine having means for carrying forwardly packets of paper, means for applying glue to a strip of cloth, means for pressing the glued cloth against the edges and the front and back sheets of the packets as they are carried forwardly, means for severing the cloth between two packets, and vertically-moving arms for receiving and carrying the bound packets until the glue becomes set, substantially as specified. 90

11. A binding-machine having reciprocating means for intermittently carrying forwardly packets of paper, means for applying glue to a strip of cloth, rolls for pressing the glued cloth against the edges, rolls for pressing the strip against the front and back sheets of the packets as they are carried forwardly, and means for carrying the bound packets until the glue becomes set, substantially as specified. 95

12. A binding-machine having horizontally and vertically movable jaws for grasping and carrying forwardly packets of paper, means for applying glue to a strip, means for pressing the glued strip against the edges of the packets, means for severing the strip between two packets, and means for carrying the bound packets vertically, substantially as specified. 100

13. A binding-machine having jaws for grasping packets of paper, means for opening and closing the jaws vertically, means for car- 105

rying the jaws forwardly and backwardly, means for applying adhesive to a strip of cloth, means for pressing the strip against the edges of the packets as they are carried forwardly, and means for severing the strip between two packets, substantially as specified.

14. A binding-machine having jaws adapted to grip and release packets of paper, a carriage holding said jaws, means arranged to open and close the jaws and to reciprocate the carriage, means for applying adhesive to a strip of cloth, means for pressing the strip about the edges of the packets when they are carried forwardly by the jaws, and shears for severing the strip between two packets, substantially as specified.

15. A binding-machine having a carriage adapted to be reciprocated horizontally, jaws borne by the carriage and adapted to be opened and closed vertically, a slide with slots arranged to open and close the jaws, a slide adapted to engage and move the slotted slide, a cam adapted to reciprocate the slide that is engaged with and disengaged from the slotted slide, and means for applying an adhesive strip to a packet carried by the jaws, substantially as specified.

16. A binding-machine having a reciprocating pusher for pushing forwardly packets of paper, opening and closing jaws for grasping the packets and carrying them farther forwardly, means for applying an adhesive strip to the edges of the packets as they are carried forwardly, means for severing the

strip between two packets, a drier having 35 vertically-movable pairs of arms, and means for delivering the packets between the pairs of arms, substantially as specified.

17. A binding-machine having a carriage bearing jaws, means for opening and closing 40 the jaws vertically, a slide adapted to be engaged with and disengaged from the carriage, means for reciprocating the slide, and means for applying an adhesive strip to a packet carried by the jaws, substantially as specified.

18. A binding-machine having a carriage bearing jaws, and a slotted slide adapted to open and close the jaws, a slide adapted to be engaged with the slotted slide for first moving the slotted slide and then the carriage, means for reciprocating the engaging slide, and means for applying an adhesive strip to a packet carried by the jaws, substantially as specified.

19. A binding-machine having a carriage bearing jaws and a block, means for opening and closing the jaws, means for inserting the block between and removing the block from between the packets of paper, means for reciprocating the carriage, and means for applying an adhesive strip to a packet carried by the jaws, substantially as specified.
